COLUMBIA PLANOGRAPH CO., WASHINGTON, D. C.

UNITED STATES PATENT OFFICE.

WILLIAM M. KLOEB, OF GIRARD, KANSAS.

FIRE-LIGHTER.

1,075,213.

Specification of Letters Patent.

Patented Oct. 7, 1913.

Application filed January 27, 1913. Serial No. 744,475.

To all whom it may concern:

Be it known that I, WILLIAM M. KLOEB, citizen of the United States, residing at Girard, in the county of Crawford and State 5 of Kansas, have invented certain new and useful Improvements in Fire-Lighters, of which the following is a specification, reference being had therein to the accompanying drawing.

10 This invention relates to an improved fire lighter, and the principal object of the invention is to provide a lighter which may be removably connected with the grate and which will light the fire at a predetermined 15 time.

Another object of the invention is to provide a mechanism for holding the match and lighting the same.

Another object of the invention is to provide 20 an improved means for releasing the match holding device, this releasing means being controlled by a clock.

With these and other objects in view this invention consists of certain novel combinations, constructions, and arrangements of parts as will be hereinafter fully described and claimed.

In the accompanying drawings:—Figure 1 is a perspective view of the fire lighter in 30 a set position. Fig. 2 is a top plan view of the fire lighter with the match holding device in a set position. Fig. 3 is a longitudinal section along the line 3—3 in Fig. 2. Fig. 4 is a transverse sectional view along 35 the line 4—4, in Fig. 2. Fig. 5 is a side elevation of a stove showing the fire lighter in position. Fig. 6 is a side elevation showing the device in a released position. Fig. 7 is a sectional view along the line 7—7, in 40 Fig. 2. Fig. 8 is a sectional view through the match holding tube. Fig. 9 is a section 45 along the line 9—9, in Fig. 8 looking toward the match holding tube. Fig. 10 is a plan view of the blank from which the supporting plate of this device is formed.

Referring to the accompanying drawings by numerals it will be seen that this invention comprises a plate 10 which is formed from a blank shown in Fig. 10. This blank 50 is provided at one end with a tongue 11 which is coiled to form a rolled flange 12. The side portions of the blank are also bent to form rolled flanges 13, which flanges permit the device to be handled without danger 55 of the hands being cut by the edges of the plate. Tongues 14 extend from the body

portion of the blank and are bent to form bearings 15 in which a shaft 16 is rotatably mounted. This shaft 16 which is preferably formed of copper wire has its ends bent to 60 form arms 17 terminating in hooks 18 by means of which the lighter is connected with the grate as clearly shown in Fig. 6. The outer end of the plate is supported by a substantially U-shape supporting member 19 65 which has its arms bent as shown at 20 and terminating in feet 21 which pass through openings formed in the plate 10. It should be noted that the space between the openings in the plate through which the feet 21 70 pass is bent to form a bearing 22, thus permitting the supporting member to be turned easily. After the hooks 18 are connected with the grate the supporting member is lowered and rests upon the shelf 46 of the 75 stove, thus supporting the outer end of the fire lighter. From an inspection of Fig. 6 it will be readily apparent that when this fire lighter is in position that the plate 10 extends outside the ash pit, thus holding 80 the clock outside the ash pit and preventing it from being damaged by ashes or burned paper or wood.

A drum 23 is mounted upon a pin 24 and carries a coil spring 25 to the end of which 85 there is secured a tube 26. A washer 23' is provided to hold the spring spaced from the upper plate of the drum. This tube 26 is secured to the spring by means of a pin 27 and is provided with a set screw 28 90 by means of which the match 29 may be secured in the tube. This drum is so positioned that when the tube is released from its holding catch that the match will pass along the roughened surface of the plate 30, 95 thus causing the match to be lighted. It should be noted that this plate 30 extends at an angle so that the match will remain in engagement with the plate from the time it strikes the plate until it reaches the end, 100 and therefore, there will be no danger of the match leaving the plate before it is caused to ignite. It will, therefore, be seen that when the match is lighted that it will be positioned close to the grate, thus causing 105 the flame to pass through the bars of the grate and light the paper or other kindling which is placed in the fire-box. The fire will then be lighted and be burning good by the time that it is necessary to use 110 the stove. The bolt 30' acts as a stop to limit the swing of the match holder.

A bracket 31 is secured to the plate 10 adjacent the drum 23 and is provided with an opening in its free end through which the end of a hook 32 is adapted to pass in order 5 to hold the tube in the position shown in Fig. 1. This hook 32 is coiled intermediate its length to form an eye 33 pivotally mounted upon a pin carried by a yoke 34. The hooked end passes through an opening 10 35 formed in the plate 10 and passes up through an opening in the plate beneath the opening in the end of the bracket 31. The shank 34 extends above the plate 10 and terminates in an eye 37 with which a cord 15 38 is connected. A clock 39 is positioned in a cradle 40, the legs 41 of which terminate in feet 42 secured to the base plate 10. This clock is held in place by a binding wire 43 and has the shaft 44 which operates the 20 alarm in the ordinary alarm clock connected with the cord 38 in order that when the alarm shaft is released the cord may be wound upon the shaft and the hook shank drawn upwardly, thus moving the hook upon 25 its pivot point and drawing the hooked end downwardly, thus releasing the tube 26 and permitting the match to be swung to the position shown in Fig. 6 and thus light the fire.

30 When operating this device the clock is set at the hour at which it is desired to light the fire and the plate is then mounted on the shelf 46 in the manner shown in Fig. 5. The hook 32 will hold the lighter in a set 35 position until the hour is reached at which it is to be released. The shaft 44 then rotates and draws the cord, thus drawing the hook downwardly and releasing the tube. It should be noted that the cord is wound upon 40 the shaft 44 between the turning link 45 and the rear plate of the clock. This prevents any danger of the cord slipping from the end of the shaft and not being wound upon it. When the tube is released it swings to 45 the position shown in Fig. 6 where it is stopped by the bolt 30' and the flammable material in the bottom of the fire-box will be ignited, thus causing the fire to be burning

and the stove to be heated when it is desired to use the stove. When the person who intends to use the fire enters the room the fire lighter is removed from the shelf and put away until it is required for further use.

It should be noted that the shaft 16 is formed from copper in order that the heat 55 may not cause the hooks to break as would be the case if it were made of some brittle metal such as iron.

Having thus described the invention what is claimed as new, is:—

1. A fire lighter comprising a base plate, a coil spring carried by said base plate, match holding means at the free end of said coil spring, a pivot bearing carried by said base plate, a hook pivotally mounted intermediate its length in said pivot bearing and having its hooked end passing through an opening formed in said base plate and positioned in alinement with a second opening whereby the hooked end may pass through 70 said base plate and engage said match carrying means to hold the same in a set position, a clock carried by said base plate, and flexible means connecting said hook with the alarm shaft of said clock for rocking 75 said hook to release said match carrying means at a predetermined time.

2. A device of the character described comprising a base plate, a shaft rotatably connected with said base plate and having its 80 ends formed into hooks adapted to connect said base plate with a grate, a supporting member having its arms terminating in feet pivotally connected with said base plate, match holding means carried by said base 85 plate, match igniting means carried by said base plate, and means carried by said base plate for releasing said match holding means at a predetermined time.

In testimony whereof I hereunto affix my 90 signature in presence of two witnesses.

WILLIAM M. KLOEB.
